James T. Timmons
his ATTORNEYS.

UNITED STATES PATENT OFFICE.

CLARENCE C. KEEHN, OF CANANDAIGUA, NEW YORK, ASSIGNOR TO THE LISK MANUFACTURING COMPANY, LTD., OF CANANDAIGUA, NEW YORK, A CORPORATION OF NEW YORK.

SUSTAINING MEANS FOR INFANTS' BATHTUBS.

1,422,718.

Specification of Letters Patent.

Patented July 11, 1922.

Application filed November 4, 1921. Serial No. 512,936.

To all whom it may concern:

Be it known that I, CLARENCE C. KEEHN, a citizen of the United States, and resident of Canandaigua, in the county of Ontario 5 and State of New York, have invented certain new and useful Improvements in Sustaining Means for Infants' Bathtubs, of which the following is a specification.

The present invention relates to sustaining 10 means for infants' bath tubs and an object of the invention is to provide a sustaining means which may be readily supported upon the ordinary large bath tub to sustain a child's bath tub. Another object of the invention is to provide a sustaining means which may be folded into compact form and will, at the same time, permit the water splashed from the child's tub to pass into the large tub over which the child's tub is 15 arranged. Still another object of the invention is to provide a sustaining means which will be durable in use, inexpensive to manufacture, and simple in operation.

To these and other ends, the invention 20 consists of certain parts and combinations of parts all of which will be hereinafter described, the novel features being pointed out in the appended claims.

In the drawings:—

Fig. 1 shows the sustaining means in plan over an ordinary large sized bath tub;

Fig. 2 shows the sustaining means in side elevation;

Fig. 3 shows the sustaining means in section and positioned over a bath tub; and

Fig. 4 is an edge view of one of the sustaining members.

Referring more particularly to the drawings, 1 indicates the large sized bath tub 40 over which the child's bath tub 2 (shown in dotted lines) is supported by the sustaining means.

The sustaining means in the illustrated embodiment comprises two members in the 45 form of boards 3, their opposed edges being provided with recesses 4 conforming to the ends of a commercially known child's bath tub 2. These boards or members 3 have, on their opposite sides of the recesses, transverse strips 5, the outer faces of which serve as abutments for cooperating with the inner walls of the bath tub 1 to prevent movement of the boards in the direction of their lengths 50 transversely of the bath tub 1. The mem-

bers 3 are connected together by flexible connections 6 which are anchored at their ends at 7 and limit the outward movement of the members 3 away from each other while permitting their movement toward each other for the purpose of collapsing the sustaining 55 means. It is preferred to arrange the chains 6 close to the recesses so that they will lie under the flange of the tub and will be protected from the dirty water splashed from the small tub.

It is apparent that a child's bath tub 2 with curved upwardly flaring ends will, when these ends are brought into engagement with the bevelled walls of the recesses 4, tend to separate the members 3 to the 60 limit of their outward movement determined by the flexible connections 6 in order to sustain the tub in an upright position, the flange of the tub resting on the boards. The members 3 rest upon the edges of a 65 bath tub 1 so that the abutment cleats 5 prevent longitudinal movement of the members 3 transversely of the tub 1. With this arrangement, the water splashed by the child passes into the tub 1 and the upper surface 70 of the members 3 may act to sustain soap, a wash rag and other materials and articles used in washing and drying the child. It is apparent that the structure may be compactly folded, is strong and durable in use 75 and is inexpensive to manufacture.

What I claim as my invention and desire to secure by Letters Patent is:—

1. Sustaining means for an infant's bath tub comprising two members having opposed receptacle receiving recesses, and flexible connections between said members of such lengths as to permit the members to be held in spaced relation to each other and so constructed as to permit the movement 90 of the members toward each other in their common plane.

2. Sustaining means for an infant's bath tub comprising two members having opposed receptacle receiving recesses, and two flexible connections connecting said members on opposite sides of the recesses of such lengths as to permit the members to be held in spaced relation to each other and so constructed as to permit the movement of the 95 members toward each other in their common plane.

3. Sustaining means for an infant's bath

tub comprising two members having opposed receptacle receiving recesses, connections between said members on opposite sides of the recesses of such lengths as to permit the members to be held in spaced relation to each other and so constructed as to permit the movement of the members toward each other in their common plane, and abutments on said members on opposite sides of the recesses for cooperating with the inner faces on opposed side faces of a large bath tub to prevent movement of the members transversely of the said tub.

4. Sustaining means for an infant's bath tub comprising two members, two flexible connections between the members between which the infant's bath tub is supported of such lengths as to permit the members to be held in spaced relation to each other and

so constructed as to permit the movement of the members toward each other in their common plane, and abutments on the under sides of the members for cooperating with the inner opposed faces of a large bath tub.

5. Sustaining means for an infant's bath tub comprising two members having opposed receptacles receiving recesses, two flexible connections connecting said members on opposite sides of the recesses, and abutment pieces secured to the under sides of the portions and on opposite sides of the recesses to cooperate with the inner faces of the side walls of a large bath tub to prevent movement of the members transversely of said large bath tub.

CLARENCE C. KEEHN.
